[57] CLAIM

The ornamental design for a case for an electronic accounting machine, as shown and described.

DESCRIPTION

FIG. 1 is a perspective view of a case for an electronic accounting machine, showing my new design; FIG. 2 is a front elevational view thereof on an enlarged scale;

FIG. 3 is a right side elevational view thereof on an enlarged scale;

FIG. 4 is a left side elevational view thereof on an enlarged scale;

FIG. 5 is a rear elevational view thereof on an enlarged scale; and

FIG. 6 is a bottom plan view thereof on an enlarged scale.

The keys are shown in broken lines for illustrative purposes only. The tray on the right side of the machine is fragmentarily shown in FIGS. 2 and 5 and omitted in FIG. 6 for convenience of illustration.

FIG. 2

FIG. 3

FIG. 4

FIG. 5

FIG. 6
